UNITED STATES PATENT OFFICE.

ANTON L. GRUBMAN, OF BELLE HARBOR, NEW YORK, ASSIGNOR TO VOICES INCORPORATED, OF NEWARK, NEW JERSEY, A CORPORATION OF DELAWARE.

SOUND-PRODUCING DEVICE.

Application filed November 22, 1924. Serial No. 751,451.

This invention relates to sound producing devices, and more particularly to a device of that type which is incorporated within the body of a doll for the purpose of simulating an infant cry, such as the exclamation "ma-ma."

It is the primary object and purpose of my present improvements to provide a device of the above character wherein the sound emission controlling means is greatly simplified in comparison with such means heretofore provided in devices of this character, while at the same time the positive and reliable functional operation of the device is assured.

In one embodiment of the invention, I provide a casing and a bellows within said casing consisting of a flexible body wall fixed at one of its ends to an end of the casing, and having a gravity movable head attached to its other end. The wall of the casing is formed at longitudinally spaced points with sound emission pockets or passages and the movable bellows head is provided with a fixed means thereon to cooperate with these pockets in the movement of said head in one direction, and thereby intermittently permit of the escape or emission of sound through said pockets whereby the desired articulation of the sound is produced.

It is a further general object of the invention to provide a sound producing device as above characterized, the several parts of which can be inexpensively produced and easily and quickly assembled so that the production and selling costs of devices of this character will be reduced to a minimum.

With the above and other objects in view, the invention consists in the improved sound producing device and in the form, construction and relative arrangement of its several parts as will be hereinafter more fully described, illustrated in the accompanying drawing, and subsequently incorporated in the subjoined claims.

In the drawing, wherein I have illustrated one simple and satisfactory embodiment of my invention, and in which similar reference characters designate corresponding parts throughout the several views,

Figure 1 is a longitudinal sectional view of the device taken approximately on the line 1-1 of Fig. 3, showing the bellows in

flated or distended with the movable head thereof positioned at the start of its operative movement;

Figure 2 is a similar view showing the bellows partly collapsed and the movable head approaching the end of its operative movement;

Figure 3 is an end elevation, and

Figure 4 is a horizontal section taken on the line 4-4 of Fig. 1.

Heretofore, in sound producing devices generally known in the art as "voices" of the collapsing bellows type, it has been customary to provide the bellows head with a movable valve and means on the casing to co-act with a part of the movable valve and open the same at the desired intervals to effect an articulation of the sound. Such devices are more or less uncertain in operation and comparatively expensive to produce. It is the aim and purpose of my present improvements to eliminate such relatively movable valve parts and to provide directly co-acting means on the movable bellows head and the casing wall whereby the emission of the sound is properly controlled to produce an articulated simulation of the word syllables. To this end, as shown in the accompanying drawing, in a simple embodiment of the device, the casing or housing 5 is in the form of a cylindrical shell, preferably stamped from sheet metal, though if desired, this casing can be produced from cardboard or other suitable material. One end of this casing is open or endless, while the other end thereof has a wall 6 provided with a series of openings 7 through which the sound is finally emitted.

Within the casing 5 a cylindrical bellows is arranged, said bellows having a flexible body wall 8 of suitable material, one end edge of which is turned outwardly around the wall of the casing 5 at its open end as shown at 9, and is securely clamped or held thereon by the circumferential clamping flange 11 formed on the end plate or cap 10 which is positioned over the open end of said casing. To the other end of the flexible bellows wall 8 a gravity movable head or weight 12 is fixed. As herein shown this head is of inverted cup-shape form and the other end of the bellows extends within the same, the end edge thereof being frictionally held and clamped against angular surfaces of said head by a metal disc 13. This disc as

well as the head wall, is centrally formed with an opening to receive a bushing 14 of cork or other compressible material, said bushing having an opening formed there-
5 through of the requisite size and shape to receive the sound producing reed 15, which may be of any desired conventional type.

A cylindrical sheet metal cap 16 is carried by the head 12, said head having a rabbet or
10 seat 17 formed in its periphery with which the marginal edge of the annular wall of said cap is frictionally engaged. The body wall of the cap 16 is disposed in spaced parallel relation to the face of the bellows head
15 12 and thus provides a chamber 18 receiving the sound waves produced by the reed 15. The annular wall of the cap 16 is provided at circumferentially spaced points with the slots 19. It will be noted that the diameter
20 of the head 12 and cap 16 is somewhat less than the internal diameter of the casing 5.

The wall of the casing 5 at longitudinally spaced points, is formed with outwardly pressed annular sections 20 of relatively different widths, thus providing spaced enlargements of the internal diameter of said casing and forming annular sound emission pockets therein.

In the operation of the device as above described, when the bellows is distended or inflated and the head 12 thereof is in the position as shown in Fig. 1 of the drawing, said head moves downwardly by gravity from such position, thereby collapsing the flexible bellows wall 8. In such gravity movement of the head 12, the air within the bellows is expelled therefrom through the reed 15, thereby producing a sound which is received in the chamber 18 carried by the bellows head.
30 In the initial portion of the movement to said head, the sound escapes from chamber 18 in relatively small volume through the slots 19 between the wall of the cap 16 and the wall of the casing 5, such sound finally emitted through the openings 7 simulating the spoken pronunciation of the letter "M", as the head 12 continues its movement, when the slots 19 come into registration with the annular pocket in the casing
35 wall formed by the first outwardly pressed section 20 thereof, the area of the emission passage between the wall of the cap 16 and the casing wall is increased and sound escapes therethrough in greater volume from chamber 18 and simulates the pronunciation of the letter "A", thus completing the sounding of the first syllable "ma". When the slots 19 pass below the first annular pocket in the casing wall, the emission of the sound is again checked by the narrowing of the sound passage and the sounding of the letter "M" is again simulated and when said slots register with the second relatively wide pocket in the casing wall, there is a final sounding
50 of the letter "A" for a relatively long period
55

of time, thereby prolonging the sounding of the second word syllable "ma". In this manner, the desired articulation of the infant cry "ma-ma" is realistically simulated. When the device is inverted from the position in Fig. 2, the gravity movable head 12 moves in the opposite direction in the casing 5 so that the bellows is inflated as the air enters the same through slots 19 and the reed 15.

From the foregoing description considered in connection with the accompanying drawings, the construction and manner of operation of my present improvements will be clearly understood. It will be seen that I have greatly simplified devices of this character by eliminating the use of relatively movable valve parts on the casing or the movable bellows head and the necessary actuating means therefor. The device is thereby also rendered exceedingly durable, and positive and reliable in its functional operation. It is also apparent that such a device is susceptible of quantity production at appreciably less cost than devices of the prior art, such as I have referred to.

While I have herein shown and described one simple, practical and satisfactory embodiment of my present improvements, it will nevertheless, be understood that the essential features of the present disclosure might also be embodied in other alternative structures. Accordingly, I reserve the privilege of resorting to all such legitimate changes in the form, construction and relative arrangement of the several parts as herein described, and as may be fairly considered as in the spirit and scope of the invention as claimed.

I claim:

1. In a sound producing device, a casing having sound emission apertures in the wall thereof, a bellows arranged within said casing having a gravity movable head, a sound producing reed through which air is expelled from the bellows in the movement of said head in one direction, the wall of said casing being also provided with sound emission passages spaced apart longitudinally of the casing, and relatively fixed means on the bellows heads cooperating with said spaced passages in the air expelling movement of said head to effect an articulated emission of the sound.

2. In a sound producing device, a casing having sound emission apertures in the wall thereof, a bellows arranged within said casing having a gravity movable head, a sound producing reed through which air is expelled from the bellows in the movement of said head in one direction, the wall of said casing being also provided with sound emission passages spaced apart longitudinally of the casing, said head having a chamber thereon receiving sound from said reed,

and the chamber wall being provided with a sound outlet opening to cooperate with said sound passages of the casing wall in the air expelling movement of said head to effect an articulated emission of the sound.

3. In a sound producing device, a cylindrical casing having sound emission apertures in one wall thereof, a bellows arranged within said casing having a gravity movable head, a sound producing reed through which air is expelled from the bellows in the movement of said head in one direction, the cylindrical wall of said casing being provided with longitudinally spaced annular sound emission passages therein, and relatively fixed means on the movable bellows head cooperating with said passages in the air expelling movement of said head to effect an articulated emission of the sound.

20 4. In a sound producing device, a cylindrical casing having sound emission apertures in one wall thereof, a bellows arranged within said casing having a gravity movable head, a sound producing reed through which air is expelled from the bellows in the movement of said head in one direction, the cylindrical wall of said casing being provided with longitudinally spaced annular sound emission passages therein, said bellows head 25 being provided with a chamber receiving the sounds from said reed, and one wall of said chamber having a plurality of spaced sound outlet openings therein cooperating with said annular passages of the casing wall in 30 the air expelling movement of the bellows head to effect an articulated emission of the sound.

40 5. In a sound producing device, a cylindrical casing having an end wall provided with sound emission apertures therein, a bellows arranged within the casing having a gravity movable head, a sound producing reed through which air is expelled from the bellows in the movement of said head in

one direction, the cylindrical wall of said casing having longitudinally spaced outwardly pressed annular sections forming spaced annular sound emission passages therein, a cylindrical cap fixed upon the bellows head and providing a chamber receiving the sound from said reed, the wall of said cap being provided with a series of circumferentially spaced openings therein cooperating with said annular passages of the casing wall in the air expelling movement of said head to effect an articulated emission of the sound.

45 6. In a sound producing device, an air chamber, a gravity movable member for causing a flow of air into and out of said chamber, a sounding reed through which the air flows in the movement of said member in one direction, and means for interrupting the emission of the sound produced by said reed including longitudinally spaced parts surrounding the air chamber and permitting of the emission of the sound in definite volume, and cooperatively related means carried by said gravity movable member and controlling such emission of the sound.

50 7. In a sound producing device, a casing open at one of its ends for the emission of sound therethrough, an air receiving chamber within the casing and a gravity movable member for expelling air from said chamber, a sound producing reed through which the air is expelled, said casing having a wall provided with spaced circumferentially continuous passages therein, and relatively fixed means carried by the air expelling member 55 and cooperating with said casing wall to control the emission of sound through said passages and effecting articulated emission of the sound.

55 In testimony that I claim the foregoing as my invention, I have signed my name hereto.

ANTON L. GRUBMAN.
